United States Patent Office

Des. 227,797
Patented July 17, 1973

227,797

PENDANT

Ronald G. Brady, 11832 162nd St.,
Norwalk, Calif. 90650

Filed Dec. 21, 1970, Ser. No. 26,586

Term of patent 14 years

Int. Cl. D11—01

U.S. Cl. D45—17

FIG. 1.

FIG. 2.

FIG. 1 is a front elevational view of a pendant, showing my new design; and

FIG. 2 is a side view thereof.

The back view is a mirror image of the view of FIG. 1.

I claim:

The ornamental design for a pendant, as shown and described.
